UNITED STATES PATENT OFFICE.

EMERSON A. BOLEN, OF MARION, INDIANA, ASSIGNOR, BY MESNE ASSIGNMENTS, OF ONE-HALF TO FRANK D. BROSIER, OF MARION, INDIANA.

MATCH-SAFE.

No. 928,023.

Specification of Letters Patent.

Patented July 13, 1909.

Application filed January 18, 1908. Serial No. 411,421.

To all whom it may concern:

Be it known that I, EMERSON A. BOLEN, a citizen of the United States, residing at Marion, county of Grant, and State of Indiana, have invented certain new and useful Improvements in Match-Safes, of which the following is a specification.

The invention relates to such improvements and consists of the novel construction and combination of parts hereinafter described and subsequently claimed.

Reference may be had to the accompanying drawings, and the reference characters marked thereon, which form a part of this specification. Similar characters refer to similar parts in the several figures therein.

Figure 1 of the drawings is a top plan view of my improved match safe. Fig. 2 is a horizontal cross-section of the same taken 20 on the broken line 2—2 in Fig. 4. Fig. 3 is a horizontal cross-section of the same taken on the broken line 3—3 in Fig. 4. Fig. 4 is a vertical section of the same taken on the broken line 4—4 in Fig. 1 showing the 25 match-lifting slides in lowered position. Fig. 5 is a vertical section of the same taken on the broken line, 5—5, in Fig. 4. Fig. 6 is a view similar to Fig. 4 with the match-lifting slides elevated. Fig. 7 is a view similar to Fig. 5 taken on the broken line 7—7 in Fig. 6.

The principal object of the invention is to deliver matches into position for removal one-by-one from a match safe, and to automatically ignite the match as the same is withdrawn from the safe.

Other objects will appear in connection with the following description.

In the preferred form of my invention the 40 match safe is combined with a cigar-cutter whereby the operation of the cigar-cutter automatically delivers a match into position to be removed from the safe and to be ignited during such removal.

45 Referring to the drawings wherein the invention is shown in preferred form, 1, represents a box or safe adapted to receive horizontally-disposed matches, 2, which are supported upon the inclined bottom, 3, of the safe. When the movable parts of the device are in their normal position of disuse, the body of horizontally-disposed matches rests in the angle formed by the bottom, 3, and a stationary cross-plate, 4, adjacent to the

lower end of the inclined bottom 3. Adjacent to the cross-plate, 4, the bottom, 3, is provided with an aperture, 5, adapted to receive one member, 6, of a pair of slides, the other member, 7, of which occupies the space between the cross-plate, 4, and the rear wall, 8, of the safe. The upper end of the slide, 6, and the upper end of the cross-plate, 4, are each inclined similarly to the bottom, 3, of the safe, while the upper end of the slide, 7, is slightly concaved to form a 65 match-receiving groove.

When the movable parts are in their normal position of disuse, the lowermost match, 2^a, in the safe will rest upon the inclined end of the slide, 6, in the angle formed thereby with the inner side of the cross-plate, 4, as shown in Fig. 4. When the slides, 6 and 7, are raised in the operation of the device, the lowermost match, 2^a, will be carried upward by the slide, 6, above the highest point 70 of the cross-plate, 4, whereupon it will roll down the inclines on the ends of the slide, 6, and cross-plate, 4, and rest against the inner side of the elevated slide, 7, in the position of the match, 2^b, as shown in Fig. 6. 80 As the lowermost match, 2^a, is carried upward by the slide, 6, the other matches being left unsupported fall back into the safe. When the slides, 6 and 7, are restored to their lowermost position, the upper end of 85 the slide, 7, will be brought to a plane just below that of the bottom of the incline on the cross-plate, 4, permitting the last previously raised match to roll down into the seat on the upper end of said slide, 7, in 90 the position of the match, 2^c, in Fig. 4.

The slide, 6, and cross-plate, 4, are preferably of a length equal to the length of the match, while the slide, 7, is of a length somewhat less than that of the match, and the 95 matches are so arranged in the safe that the head-portion of a match resting in the seat on the upper end of the slide, 7, will overhang and project beyond said slide, 7, in position to be engaged by the stop, 9, located in the path of the head-portion of the match as the same is carried upward by the slide, 7, by engagement with which stop the match is tipped, as indicated by dotted lines, 2^d, in Fig. 5, and turned from a horizontal position to a vertical position, as that occupied by the match, 2^e, as shown in Figs. 6 and 7, in which position it is sup-

ported between the inner vertical edge of the slide, 7, and the stop, 9, both of which are grooved to receive the match.

The stop, 9, is mounted upon the upper end of a plate-spring, 10, whereby it is made yielding; and the strength of the spring, 10, is sufficient to cause the slide, 7, to be frictionally held in its raised position so long as the match remains between the vertical grooved edge of the slide, 7, and the stop 9.

As the match is tipped into vertical position it is brought into line with the delivery aperture, 17, in the top of the safe, and as the raising of the slide, 7, is completed, the end of the match is forced out through said delivery aperture into position to be grasped by the fingers of the operator and forcibly removed from the safe.

Any known means for lighting the match may be employed.

One of the objects of my invention is to cause the automatic ignition of a match by its withdrawal from the safe, and, if matches are employed the entire heads of which are adapted to be ignited by friction, this object may be accomplished by locating in the path of the head of the match, as the same is withdrawn from the safe, an abrasive body which may be of any known form. In the preferred form of my invention I have shown a device adapted to automatically ignite what are known in the trade as "safety" matches or "bird's eye" matches, the tip portions only of the heads of which are adapted to be ignited by friction. For this purpose I have shown adjustably mounted upon the stop, 9, a needle, 11, inserted through an aperture in said stop with its point projecting slightly beyond the grooved face of the stop at the upper end thereof. As the match is drawn upwardly between the slide, 7, and the stop, 9, just as the head of the match leaves the stop, 9, the force of the spring, 10, will cause the stop to move inwardly carrying the point of the needle, 11, across the end of the match, thus igniting the same. The needle, 11, is secured in adjusted position by means of the set-screw 12. The inward movement of the spring, 10, is limited by a stop 13.

For certain purposes of the invention the slides, 6 and 7, can be raised and lowered in any known manner. I have shown said slides projecting upwardly from a common support or block, 14, located in the path of the movable member, 15, of a known form of cigar-cutter, a detailed description of which is unnecessary for the purpose of the present invention, for which purpose it is only necessary to understand that the lever, 15, is so connected with the cigar-cutting mechanism, 16, that the operation of the cigar-cutter causes the inner end of said lever, 15, to be raised and brought into engagement with the block, 14, whereby the

slides, 6 and 7, are raised. For this purpose any movable member of a cigar-cutter may be employed.

In Fig. 4 the cigar-cutter is shown in its position of disuse, while in Fig. 6 it is shown in the position which it assumes in use.

What I claim as new and desire to secure by Letters Patent is—

1. In a device of the class described, the combination with a vertically-movable member provided on its upper end with a seat for part of a match horizontally-disposed, and on a neighboring vertical edge with a seat for the remainder of the match vertically-disposed; of means whereby matches are automatically delivered one at a time to said movable member with a part of the match occupying said horizontal seat and the remainder of the match overhanging said vertical seat; means for moving said movable member; a stop yieldingly movable transversely of the path of the overhanging portion of said match, said stop being cooperative with said vertical seat to support a match in vertical position therein; adjustable means for limiting the movement of said stop toward said member and a frictional match-igniter mounted upon said stop in the path of the head of a match being withdrawn from said vertical seat.

2. In a device of the class described, the combination with a pair of members adapted to embrace between them a match; yielding means for moving one of said members transversely of the match toward the other; of means for delivering matches, one at a time, between said members, and an igniting pin on said movable member, adapted to be carried thereby transversely of the match into engagement with the tip of the head of the match being withdrawn from between said members.

3. In a device of the class described, the combination with a vertically-movable member provided on its upper end with a seat for part of a match horizontally-disposed, and on a neighboring vertical edge with a seat for the remainder of the match vertically-disposed; of means whereby matches are automatically delivered one at a time to said movable member with a part of the match occupying said horizontal seat and the remainder of the match overhanging said vertical seat; means for moving said movable member; a stop in the path of the overhanging portion of said match, said stop having on the side neighboring said movable member a grooved seat for a vertically-disposed match; means for yieldingly forcing said stop toward the match-supporting vertical edge of said movable member; and an upwardly-pointing match-igniting pin mounted upon said stop and adapted to traverse the tip of the head of a match as the same is withdrawn from said vertical seat.

4. In a device of the class described, the combination with a pair of coöperating members adapted to receive therebetween the head-portion of a match; of means for yieldingly forcing one of said members toward the other transversely of the path of the match and a removable pin carried by said movable member adapted to traverse the

tip of the head of a match being withdrawn from between said members. 10

In testimony whereof, I have hereunto set my hand this 10th day of January, 1908.

EMERSON A. BOLEN.
